UNITED STATES PATENT OFFICE

CHARLES H. CALDWELL, OF BROCKTON, MASSACHUSETTS, ASSIGNOR TO GEO. E. KEITH COMPANY, OF CAMPOLLO, MASSACHUSETTS, A CORPORATION OF MASSACHUSETTS

DESIGN FOR A SHOE

Application filed November 26, 1932. Serial No. 46,188. Term of patent 7 years.

To all whom it may concern:

Be it known that I, CHARLES H. CALDWELL, a citizen of the United States, residing at Brockton, in the county of Plymouth, and State of Massachusetts, have invented a new, original, and ornamental Design for a Shoe, of which the following is a specification, reference being had to the accompanying drawing, forming part thereof.

The drawing represents a side view of a shoe embodying the design, the opposite side being substantially the same.

The essential feature of the invention resides in ornamenting the vamp and quarter of a shoe with the design shown. As the design is applicable to shoes of various shapes and styles the representation of shoe is merely conventional, for showing an application of the design.

I claim:

The ornamental design for a shoe, as shown and described.

CHARLES H. CALDWELL.
